UNITED STATES PATENT OFFICE.

JOHN R. MILSON, OF MANSFIELD, MASSACHUSETTS, ASSIGNOR OF ONE-FOURTH TO
CHARLES E. MILSON, OF PROVIDENCE, RHODE ISLAND.

OILER FOR SPINNING MACHINES.

Application filed January 2, 1926. Serial No. 78,858.

This invention relates to an improved construction of oiling device more particularly adapted for cap spinning machines; and has for its object to provide simple and effective means for oiling the bearing portion of the package carrying tube, as it is rapidly rotated on the spindle, from the oil reservoir which is carried on the lift rail.

10 A further object of this invention is to mount one or more oil pads in the reservoir, one of the pads being in contact with the spindle, and to also provide a lid for the reservoir having an oil-measuring recess in its face and air and oil holes through it communicating with the reservoir below for supplying both oil and air to this reservoir to conduct the oil thereto when applied and also to prevent the forming of a vacuum 20 in the reservoir to permit the rapid rotation of the tube to lift the oil from the reservoir and lubricate the spindle and tube throughout the length thereof when it bears upon the spindle.

25 A still further object of this invention is to concave the under surface of the lower flanged portion on the tube-driving whirl, which portion is arranged to extend down into the oil-measuring recess of the lid and 30 cover the oil and vent holes therein to create by its rapid rotation an air pressure and direct the same downwardly through the oil holes to act upon the oil held in the pads in the reservoir and assist the rapidly rotating tube to lift the oil upwardly through 35 the pads to lubricate the spindle and the tube during the reciprocating travel of the latter.

With these and other objects in view, the 40 invention consists of certain novel features of construction, as will be more fully described, and particularly pointed out in the appended claims.

In the accompanying drawings:

45 Figure 1 is a sectional view illustrating my improved oiling device as applied to a cap spinning machine, a portion of the bolster and lift rails being herein shown in section.

50 Figure 2 is a sectional view showing a detail of my improved oil reservoir cup.

Figure 3 is a sectional view showing a detail of the lid member designed to fit down

into the oil reservoir and also designed to support the whirl and its yarn package 55 carrying tube.

Figure 4 shows the oil reservoir as mounted on the lift rail and showing the pads in the reservoir with the lid in position, supporting the package tube whirl.

Figure 5 is a section on line 5—5 of Figure 4.

Figure 6 is a side elevation showing a portion of the end of the lift rail with a stop or lug formed on the reservoir cup to prevent relative rotation of the reservoir on the rail.

It is found in the practical operation of cap spinning machines, very difficult to oil the rapidly running package carrying tube 70 while traversing vertically on its spindle, sufficiently to prevent undue wear even though oil be applied to this old style spindle two or three times a day, and even then portions of the tube become dry which 75 greatly limits the working life thereof, but by the use of my improved fountain type of oiler the attendant needs only to apply oil to the reservoir but once in two weeks instead of twice a day, as by the old method, 80 and instead of leaving a portion of the tube dry by this old hand-oiling method any desired amount of oil may be forced up inside the tube to keep the same fully lubricated, which is accomplished by simply changing 85 the shape of that portion of the lower flange of the whirl that sets into the oil recess in the lid member and also by adjusting its vertical position in the recess; also by the use of my improved oiling device which provides perfect lubrication for the tube, the 90 power required for driving the package carrying whirl is greatly reduced, the wearing life of this mechanism is greatly increased and the tube being so properly oiled 95 will run at a more uniform speed thereby setting a more uniform twist in the yarn and so produce a yarn of a much higher quality and of greater value; and the following is a detailed description of the present embodiment of my invention and showing one construction of oiling device by which these advantageous results may be accomplished:

With reference to the drawings, 10 designates the bolster rail of the usual cap spin-

ning machine, which carries the spindles 11, and 12 designates the lift rail on which the package driving mechanism is mounted and by which this mechanism is raised and lowered in the cap 13 to lead the yarn to be wound evenly onto the bobbin 14 as it is raised and lowered in the cap. The package is carried on the tube 15 to which tube is connected the whirl 16 that is driven by a belt (not shown) to rotate the same at a high velocity during the bobbin winding operation.

My present invention provides simple and effective means for lubricating the spindle 15 and the inner surface of the tube which contacts therewith for the purpose of reducing the driving friction of the tube, to obtain a more uniform twist in the yarn to prolong the operating life of the tube, and to reduce the driving power to the minimum, and to accomplish these advantageous results I have formed a cup-shaped reservoir 17 adapted to rest upon the lift rail 12, the cup being provided with a central opening 9 through which the spindle 11 extends. The side wall of this reservoir being provided with a lug or lip 18 to set down over the edge of the lift rail 12 in the manner illustrated in Figure 6, for the purpose of preventing relative rotation of the reservoir cup on the rail. This reservoir cup is provided with a lid member 19 which has a body portion 20 arranged to set down into the reservoir and is recessed at 21 for the purpose presently described. The lid being provided with a recess or keyway 31 to receive a pin 32 to prevent relative rotation between the lid and cup.

The upper face of this lid is recessed as at 22 to provide an oil measure to determine just the proper quantity of oil to be deposited therein at a time, which is required for the complete saturation of the three superimposed oil storing pads 23, 24 and 25. The pads 23 and 24 being preferably of a size to entirely fill the space in the reservoir while pad 25 is arranged to contact with the surface of the spindle so as to lubricate the same during the vertical traverse of the package carrying tube thereon.

This lid member 19 is provided with one or more holes 26 through its face communicating with and permitting the oil from the recess above to drop down and saturate the pads in the reservoir below. The upper central portion of this lid is provided with an upstanding shoulder 27 presenting a suitable bearing for the support of the whirl 28 thereon, which shoulder has a central opening 33 through which the spindle extends.

The lower portion of this whirl 28 is provided with an annular flange 29 which extends slightly downwardly to project into the oil recess 22, but to run clear of the bottom thereof and the under side of this

flange is concaved as at 30 whereby a rapid rotation of the whirl has a tendency to give the air pressure created in the concaved space beneath, a downward direction so as to force the air with slight pressure through the oil holes 26 to act upon the oil in the pads and force the same upward into the pad 25 in contact with the spindle to cooperate with and assist the action of the rapidly rotating tube to further act upon the oil in this pad 25 and lift the same up through the tube to the very top thereof and so thoroughly lubricate the spindle and the tube throughout the entire length of the latter. In other words, the traverse of the tube on the spindle may be 4½" while the length of the tube may be 6" and the oil by my improved method will travel to the very top of the tube and fully lubricate the same throughout its entire length. 85

It will be noted that by my improved construction the lubricating pad that contacts with the spindle sets up inside of the lower edge of the whirl, in close proximity to the point of greatest strain and greatest friction due to the tension of the driving band on the whirl. 90

My improved oiling device is extremely simple in construction and is effective in its operation and by its use the spindle and the tube are completely lubricated. 95

It is found in practice by changing the shape of the concavity of the under side of the flange, and the distance the flange extends into the recess in the lid will vary to considerable extent the amount of lubricating oil which will flow up through the tube. 100

The foregoing description is directed solely towards the construction illustrated, but I desire it to be understood that I reserve the privilege of resorting to all the mechanical changes to which the device is susceptible, the invention being defined and limited only by the terms of the appended claims. 105

I claim:

1. In a spinning machine the combination with the spindle and package carrying tube and its driving whirl, of an oiling device for the tube and spindle comprising an oil reservoir carried by the lift rail of the machine, the bottom wall of said reservoir having a spindle receiving opening and an oil retaining upturned flange about said opening, a lid for said reservoir having a hollow central upwardly extending whirl support and provided with oil and air openings, a lubricating pad in said support in contact with the spindle and supplied with oil from the reservoir, the lower belt guide flange on said whirl being concaved to receive said support and position said oil pad in proximity to the lower edge of the whirl, the rapid rotation of the whirl acting upon the oil in the reservoir to lift the same up through said tube. 115 120 125 130

2. In a spinning machine, the combination with the spindle and package carrying tube and driving whirl, of an oiling device for the tube and spindle, comprising an oil reservoir supported on the lift rail of the machine, an oil pad in the reservoir, the bottom wall of said reservoir having a spindle receiving opening, an oil retaining upturned flange about said opening, a lid member on the reservoir having combined oil and air holes communicating with the reservoir below, said whirl having a flange of a size to cover said holes and having a bottom surface formed to adapt it to force air downwardly thru the holes upon rapid rotation of said spool, the rapid rotation of the whirl and tube serving to cause the oil in the reservoir to move upwardly to lubricate the contacting surface of the tube and spindle.

3. In a spinning machine, the combination with the spindle and package carrying tube and driving whirl, of an oiling device for the

a downwardly directed air pressure through 50 said holes to assist in directing the oil upwardly through said pad and tube.

5. In a spinning machine, the combination with the spindle and package carrying tube and its driving whirl, of an oiling device for 55 the tube and spindle comprising an oil reservoir carried by the lift rail of the machine, an oil pad supplied with oil from the reservoir in contact with the spindle, a lid member on the reservoir having an annular recess in its upper face, a raised central bearing member for the whirl and tube having a central spindle receiving opening and having air and oil holes communicating with the reservoir below, the whirl said whirl 65 having an annular belt guiding flange extending downwardly into said recess in the lid but clear of the bottom wall thereof, the under surface of said flange being concaved to direct a current of air downwardly 70 through said holes to act upon the oil be-
